UNITED STATES PATENT OFFICE.

ALVA T. SMITH, OF WATERBURY, CONNECTICUT.

DESIGN FOR AN ELECTRIC RANGE.

Application filed September 11, 1926. Serial No. 19,036. Term of patent 14 years.

To all whom it may concern:

Be it known that I, ALVA T. SMITH, a citizen of the United States, residing at Waterbury, county of New Haven, and State of Connecticut, have invented a new, original, and ornamental Design for Electric Ranges, of which the following is a specification, reference being had to the accompanying drawing, forming part thereof.

In the drawing, the figure is a perspective view of the electric range.

I claim:

The ornamental design for an electric range as shown.

ALVA T. SMITH.
